COMPRESSOR UNLOADER

Ellis Nathan, Easton, Pa., assignor to Pennsylvania Pump & Compressor Co., Easton, Pa., a corporation of Pennsylvania

Application November 17, 1933, Serial No. 698,386

2 Claims. (Cl. 230—29)

This invention relates to compressors for air and other gases and in particular to an unloading device for a single acting double cylinder air or gas compressor.

5 A primary object of the present invention is to provide a simple form of unloader adapted to simultaneously unload the cylinders of a compressor having adjacent single acting pistons by movement of a single valve contacting member.

10 One feature which enables me to accomplish the above mentioned object is that a member is provided having fingers engaging the intake valves of the adjacent cylinders, this member being moved to engage or disengage the intake 15 valves by a pressure responsive device.

With the above and other objects in view, my invention includes the features of construction and operation set forth in the following specification and illustrated in the accompanying 20 drawing.

In the accompanying drawing annexed hereto and forming a part of this specification, I have shown my invention embodied in a small size air compressor having single acting pistons in 25 adjacent parallel cylinders, but it will be understood that the invention can be otherwise embodied and that the drawing is not to be construed as defining or limiting the scope of the invention, the claims appended to this specification being relied upon for that purpose.

30 In the drawing the figure is a vertical sectional view of a complete compressor provided with the novel unloading means.

In the above mentioned drawing I have shown 35 but one embodiment of the invention which is now deemed preferable, but it is to be understood that changes and modifications may be made within the scope of the appended claims without departing from the spirit of the invention.

40 Briefly, and in its broadest aspect, my invention may include the following principal parts: First, a compressor cylinder casing having adjacent parallel cylinder openings therein; second, a cylinder head secured to said casing; third, discharge valves secured within said head and connecting the space within each cylinder with discharge passages; fourth, inlet valves within said head admitting air from space 45 surrounding the head to the space within the cylinders; fifth, a cover plate for said inlet valves secured to said head; sixth, clamping means for said inlet valves retained in place by said cover plate; seventh, a member movable within said 50 inlet valve cover plate and having extensions

contacting with said intake valves, and means to move said member to render said intake valves operative or inoperative.

Referring more in detail to the figure of the drawing, I provide a cylinder casing 10 within 5 which are provided parallel cylinder openings 11. Supporting the casing 10 is a base 12 having a main crank shaft 14 extending therethrough and driven by any suitable source of power at one end. Within the openings 11 operate pistons 13 10 shown as of trunk form connected to the main crank shaft 14 by connecting rods 15 of standard or conventional type. It will be noted that the pistons are single acting and compress air or gas by admitting and discharging the air or 15 gas to and from one end only.

Secured to the end of the casing opposite that to which the base 12 is secured is a cylinder head 18 within which are mounted discharge valves 19 one being shown for each cylinder. These 20 discharge valves 19 have their assemblies retained in place against a recessed seat in the cylinder head 18 by a clamping screw 20 threaded through a small valve cover 21 above the valve 19 and secured by any appropriate means (not 25 shown) to the cylinder head 18. As the discharge valves and their assemblies and retaining means form no part of the present invention and are or may be of old and well-known types, further description is not thought to be necessary. The space above the valves 19 and within 30 the cylinder head 18 forms a discharge passage 22 for the compressed gases delivered from both cylinders. This space 22 is in the form of an annulus, the inner periphery or wall of which is 35 formed by a partition 23 forming an integral part of the cylinder head or cover plate 18. In the outer wall of this annulus a discharge pipe of any type (not shown) may be connected by means of an opening 45 the surface of which 40 may be suitably threaded.

Secured also within recessed openings in the cover plate or cylinder head 18 are intake valves 25, one being shown for each of the cylinders. These intake valves 25 are old and well-known 45 so that a description will be unnecessary. These valves are mounted within the circular partition or wall 23 forming an integral part of the head 18 and separating the discharge space 22 from the space within the wall 23 to which air to be 50 compressed is admitted. To retain the assemblies for the intake valves 25 in position clamping members 26 are provided. One of these members 26 is provided for each intake valve 25. These members 26 are in the form of short hollow cylinders, 55

the valve engaging or lower ends being tapered as shown and their opposite ends being engaged by a circular cover member 27 secured by any appropriate means such as headed screws 42, two only of which are shown, to the cylinder head 18. Openings 28 are provided through the cover member 27 through which incoming air may enter the intake valves 25 and the cylinders 11. The clamping members 26 as shown in the figure are 10 cut away upon one side, these portions facing each other for a purpose presently to be described.

Slidably mounted within the member 27 is a short rod 29 having at its lower end, as viewed in the figure, a member 30, the extended and bent 15 down arms 31 of which enter the assemblies for the intake valves 25. In the lowermost position of the rod 29 and member 30 the ends of the arms 31 contact with and hold the intake valves 25 in an inoperative position. In the upper positions 20 of this member 30 the arms 31 are disengaged from the intake valves 25 so that these valves 25 can function normally.

In order to operate the rod 29, its upper end is enlarged and over this is placed a diaphragm 32 25 of rubber or other flexible and impervious material. The diaphragm 32 has its periphery clamped between portions of the cover member 27 and a concaved plate 33 forming a pressure tight compartment above the diaphragm 32. By admitting 30 air under pressure to the space above the diaphragm 32 the member 30 is forced down against the pressure of a spring 34 normally resiliently holding the member 30 and rod 29 in their upper positions. By admitting and exhausting air under 35 pressure to and from the space above diaphragm 32 the intake valves may be rendered inoperative or operative thus unloading or loading the compressor as desired.

To control the admission of air to the space 40 within plate 33 and above the diaphragm 32 any form of regulator such as the centrifugal starting regulator 35 may be employed. As this form of unloader regulator may be of standard 45 form, no further description is thought to be necessary. Through this regulator 35 air under

pressure may be admitted from a connection 36 from the compressor receiver to a pipe 37 connected to the plate 33 during starting of the compressor.

In addition to the fluid pressure means to move 5 the member 30 downward, a supplemental manual means may be provided. These means may include a rod 38 extending through plate 33 and pressing against the diaphragm 32 and rod 29. A spring 39 normally holds this rod upward so 10 that a head 40 thereon forms a pressure tight seat against the plate 33 when in uppermost position. A handle 41 pivoted to the plate 33 enables the rod 38 to be forced downward to depress the rod 29 and member 30. 15

I claim:

1. An unloading device for compressors having adjacent parallel cylinders, a cylinder head covering the entire end thereof, and discharge valves mounted in said head within an annular 20 discharge passage formed therein, said unloading device comprising in combination, intake valves for each of said cylinders mounted within the central portion of said head, a circular member contacting with said valves and retaining them individually in place, and unitary means mounted on said head and having integral members extending to and contacting with each of said intake valves whereby said intake valves may be moved simultaneously to inoperative positions. 25

2. An unloading device for compressors having adjacent parallel cylinders, a cylinder head covering the entire end thereof, a circular partition within said head, and discharge valves in said head within a discharge passage on the outside 30 of said partition, said unloading device comprising in combination, intake valves centrally disposed in said head within said partition, means to admit air to said intake valves, a cover plate secured to said head for retaining said intake valves in position, and fluid-operated means supported in said cover plate for rendering said intake valves inoperative. 35
